FATTY ACID DISTILLATION

Victor Mills, Cincinnati, Ohio, assignor to The Procter & Gamble Company, Cincinnati, Ohio, a corporation of Ohio

Application February 26, 1940, Serial No. 320,825

8 Claims. (Cl. 202—46)

This invention relates to a continuous process for distilling higher fatty acids from materials containing the same, and more particularly concerns a process for the dry distillation of such materials, that is, distillation without the use of steam or other added gaseous medium.

This application is related to my pending application, Serial No. 321,306, filed February 28, 1940, which is a continuation-in-part of application Serial No. 245,440, filed December 13, 1938, in which I have described a method for the distillation of free fatty acids from fatty acid containing materials involving heating the stock to a temperature sufficiently high that the latent heat required for vaporization of most of the fatty acids is contained therein, introducing the heated material into a hot liquid body of undistilled residue contained within a zone maintained at low absolute pressure whereupon most of the free fatty acids vaporize substantially instantaneously, employing the vapors thus formed to effect continuous circulation of undistilled residue in accordance with the air-lift principle and/or the ejector principle, continuously withdrawing the vapors from the low pressure zone and condensing same, and continuously withdrawing excess undistilled residue from said zone.

To effect vaporization under these conditions of substantially all of the vaporizable fatty acids in a hydrolyzed material such as tallow or grease, for example, would require preheating the stock to a temperature in the neighborhood of 650° F. Under such drastic heat treatment the odor of the distillate is very often impaired even though the preheating and subsequent flashing steps are promptly carried out. Under preferred operating conditions as described in my related pending application above referred to, the stock is preheated to a temperature in the range of about 550—575° F. whereby 75—80% of the distillable fatty acids are vaporized. The unvaporized residue is normally collected and stored until a sufficient quantity has been accumulated and then re-run through the apparatus in a manner similar to that used on the original material. The fatty acid additionally removed by this secondary distillation step increases the total distillate to as much as 88—95% of the distillable fatty acid in the original material fed to the still.

There are disadvantages even in such an efficient method of operation. For example, the first residue issues from the still at such a high temperature that, unless cooled, unavoidable oxidation with resultant darkening of the ma-

terial takes place. Furthermore subsequent separate distillation of the undistilled residue results in a distillate fraction having different characteristics than the original distillate obtained and therefore there exists a certain amount of fractionation which may be undesirable. Also when the cooled residue is subsequently subjected to distillation a material amount of heat must again be added to bring the stock to distillation temperature.

The present invention is directed toward obtaining the higher percentage of fatty acid distillate without allowing the undistilled residue from the first operation to cool down appreciably or to come in contact with the atmosphere.

In accordance with my invention the hot residue from the first distillation step is pumped under vacuum from the first distillation device, through a reheater, and then conducted into a secondary still which may be constructed, for example, either separately from the primary still or within the primary still.

My invention will be more fully understood from the following description taken in conjunction with the appended drawing in which

Figure 1 illustrates diagrammatically one form of distillation apparatus which may be used in the practice of my invention, the secondary still being within the primary still, and

Figure 2 illustrates diagrammatically another form of distillation apparatus which may be employed in the practice of my invention, the secondary still being outside of the primary still.

Referring now to Figure 1, numeral 3 represents a source of supply for the fatty acid containing material such as a feed tank, and pump 4 delivers said material through pipe 5 and feed control valve 6 to the primary heating unit 7 such as a heat exchanger, thence through pipe 8 into the still 9. The still 9 is provided with a primary undistilled residue basin 10, a primary circulating tube 11, open at its ends 12 and 13, and a primary baffle 14. The undistilled residue which collects in basin 10 is continuously drawn off through pipe 15 by means of pump 16 and delivered through pipe 17 and control valve 18, secondary heater 19, and pipe 20 into bottom end 21 of the secondary circulating tube 22 within the secondary basin 23. Secondary baffle 24 is employed to accomplish the same purpose as primary baffle 14, which purpose is described in detail below. Secondary undistilled residue from the secondary basin 23 is conducted by pipe 25 to receiver 26 which may be continuously or inter-

mittently emptied as desired by means of pump 27. Vapor pipe 28 conducts the combined fatty acid vapors of the primary and secondary distillation steps to suitable condensing equipment not shown.

The apparatus shown in Figure 2 is essentially the same as that shown in Figure 1 except that the secondary basin 23 is an integral part of a secondary still 29 which is connected to still 9 by means of a secondary vapor pipe 30.

The apparatus shown in Figure 1, for example, may be operated as follows: The material to be distilled, containing a substantial amount of higher free fatty acids, is drawn from tank 3 and pumped by means of pump 4 through pipe 5 and feed control valve 6 to the primary heater 7 wherein the material is heated to a sufficiently high temperature so that the necessary latent heat of vaporization of most of the fatty acids is contained therein. The heated fatty acid containing material is then conducted through pipe 8 to still 9 which is maintained at an absolute pressure of about 0.5 inch of mercury or less, such as 0.05 to 0.1 inch of mercury, and wherein substantially instantaneous vaporization of most of the fatty acids takes place. As above described, the still comprises a primary residue basin 10 in which is substantially centrally located a primary circulation tube 11. The relative vertical position of this tube is so adjusted that its bottom end 12 is submerged in the undistilled residue in the still basin 10 and that its top or outlet end 13 is above the surface of the undistilled residue. Suitably located above the primary circulating tube 11 is a circular, umbrella-shaped, primary deflection baffle 14. As will be noted from the drawing, the heated fatty acid material as introduced into the still is directed upward within the tube 11. Since the fatty acid material is heated sufficiently to effect substantially instantaneous vaporization of unvaporized fatty acids at the pressure within the still, fatty acid vapors will immediately form and by the air-lift principle and/or the ejector principle will cause flow of undistilled residue and fatty acid vapors up the tube 11 and against baffle 14. Further expansion of that portion of the fatty acids vaporized in the heat exchanger 7 also takes place due to the reduced pressure in the still. The velocity of the mixture of vapor and undistilled residue is such that as the undistilled residue strikes the baffle 14 a curtain of liquid is formed, which curtain may be directionally controlled by the shape of the baffle. I have found that this curtain is very effective in removing entrainment ordinarily accompanying flash distillation, probably because of the intimate contact of the vapor with the liquid residue.

The undistilled residue continues to collect in the basin 10 as distillation progresses, any excess above the predetermined amount to be kept in the basin for circulation being removed by pump 16 through pipe 15 and delivered through pipe 17, control valve 18 to the secondary heater 19 wherein the undistilled residue is reheated so as to incorporate therein sufficient heat for vaporization of fatty acids contained in said undistilled residue. The heated residue passes through pipe 20 and is introduced into the bottom end 21 of the secondary circulating tube 22 contained in secondary residue basin 23. As in the case of the first step of the distillation, fatty acids contained in the heated material volatilize and thereby project an admixture of same with secondary undistilled residue against the sec-

ondary baffle 24 whereby a curtain of secondary undistilled residue is formed. The undistilled residue over and above that required for circulation in the secondary basin 23 is continuously drawn off through pipe 25 to receiver 26 from which the residue may be pumped continuously or intermittently as desired. The fatty acid vapors from the primary and secondary distillation steps combine within the vaporization zone of the still 9 and pass through vapor pipe 28 to suitable condensing equipment.

As above described in the case of Figure 2, a complete secondary still 29 may be constructed in a manner similar to the construction of still 9 except, of course, preferably on a smaller scale. The fatty acids volatilized in still 29 in this case pass through vapor pipe 30 and either may be condensed separately from the vapors of the primary distillation or may be combined therewith and passed through the vapor pipe 28 to suitable condensing equipment. The undistilled residue from the secondary distillation step is, of course, removed in a manner similar to that above described or if desired may again be reheated and subjected to distillation conditions.

While the above description gives in detail the general aspects of my invention, improvements such as the following may be incorporated, the essential features of said improvements being diagrammatically shown by dotted lines in the drawing. It is obvious that vaporization of the fatty acids in the fatty-acid-containing material requires a certain amount of latent heat which must be available at or above the fatty acid vaporization temperature corresponding to the operating pressure. An increase in volume of material being heated without a corresponding increase in weight of fatty acid to be vaporized makes possible a reduction in temperature to which the stock must be heated in order that it contain sufficient sensible heat to vaporize that fatty acid. Therefore by recirculating a portion of the undistilled residue and thereby "diluting" the incoming fatty-acid-containing material the advantages of lower temperatures may be realized. If, however, temperature is not an item of concern and pressure is, then of course, the "diluted" material may be heated to the same temperature that is used in operations not employing recirculation, thereby incorporating a larger amount of available heat for vaporization of the free fatty acids in the mixture and making possible operation at a higher pressure within the still.

If it is desired to recirculate a portion of the primary undistilled residue and thereby realize advantages as above pointed out, then valve 40 in pipe 41 returning to the inlet side of the heater and valve 42 in pipe 17 leading to the secondary heater may be adjusted to give the desired amount of recirculation, the temperature to which the mixture is heated and/or the pressure on the still 9 being appropriately adjusted. Similarly recirculation of secondary residue may be effected by proper control of valve 43 and valve 44 in pipe 45. A pump 46 in the discharge pipe 25 will work to advantage if secondary residue is recirculated.

It will be noted that the feed control valves 6 and 18 are located in the inlet pipes to the heat exchangers. Thus in the preferred practice of my invention I do not take the precaution to maintain sufficient pressure on the material in the heat exchangers to prevent vaporization of the fatty acids therein. As a matter of fact the

material passing through the heat exchangers in accordance with my preferred process is subjected to a progressive reduction in pressure due to resistance to passage of the stock through the heater, for example, from about 20 pounds to about zero pounds gage pressure whereby a mixture of superheated liquid and fatty acid vapors are formed before introduction into the still proper. This arrangement differs over prior practice of flash distillation and has presented at least two advantages. First, the control valve is subjected to throttling relatively cool fatty acid containing material rather than hot material, thereby greatly reducing the corrosive action of the fatty acids on the valve, and, second, some of the fatty acids are permitted to volatilize on passage through the heat exchanger and thus the temperature of the material need not be carried as high as would be necessary if pressure were applied to prevent any fatty acid volatilization.

The raw materials containing fatty acids for use in my process may consist of any fats or fatty oils or materials containing same such as garbage grease or acidulated soap stock from the refining of fats and oils. In the case of the specific stocks mentioned, any neutral fat in same should, of course, be hydrolyzed to fatty acid and glycerin to as high degree as possible and the fatty acid separated before being subjected to distillation. Garbage grease or acidulated soap stock so hydrolyzed will usually contain about 90 per cent or more of free fatty acid calculated as oleic acid. Of course these stocks or lighter colored stocks such as tallow and palm oil, which sometimes contain 25 to 50 per cent free fatty acid, may be subjected to distillation without hydrolysis in accordance with the present invention in order to remove substantially all of the free fatty acid contained therein. The undistilled residue resulting from this application of my process on oils such as palm oil is exceptionally light in color and may be used directly for any suitable purpose.

As a specific example of my procedure carried out in accordance with the method illustrated diagrammatically in Figure 1, no recirculation being employed, impure fatty acids resulting from the hydrolysis of tallow are heated continuously in primary heater 1 to a temperature of 550-575° F. and are introduced into the lower end 12 of the primary circulating tube 11 of still 9 which is maintained at a pressure of about 0.08 inch of mercury absolute pressure. Approximately 75-80 per cent of the stock volatilizes immediately and causes circulation of the primary undistilled residue contained in the basin 10 whereby said undistilled residue is projected upwardly against the primary baffle 14 and deflected so as to form a curtain of undistilled residue outward, downward, and away from the vapor outlet. The temperature immediately drops due to volatilization of fatty acids and the fatty acid vapors at a temperature of about 450° F. pass through the vapor pipe 28 to suitable condensing equipment. The undistilled residue, which consists of about 20-25 per cent of the stock fed and which likewise has dropped in temperature to approximately 450° F., is removed by means of pump 16, reheated in the secondary heater 19 to 575-590° F., and introduced into the bottom end 21 of the secondary circulation tube 22 contained within the secondary basin 23. Fatty acids contained in the heated residue are volatilized, become admixed with secondary undistilled residue

5 contained in the basin 23 and the admixture is projected upward against the secondary baffle 24, the fatty-acid vapors thus formed combining with the fatty acid vapors evolved in the primary distillation step and passing off to suitable condensing equipment through the vapor pipe 28. The fatty acids actually vaporized and condensed amount to approximately 95 per cent of the stock fed to the still, the remaining five per cent being 10 undistilled and/or undistillable residue which is continuously drawn off through pipe 25 to receiver 26.

15 The same process can of course be carried out in accordance with the method diagrammatically shown in Figure 2, the fatty acid vapors from the primary and secondary distillation steps being either combined and condensed together or condensed separately. In the preferred arrangement, however, the secondary equipment is located within the primary still, since by this arrangement there is less heat loss and the secondary still need not be air tight.

20 The advantages of recirculation as above described may be exemplified as follows. By recirculating primary undistilled residue in amount equal to about thirty-four per cent of the feed of the original fatty-acid-containing material to the primary circulating tube and by recirculating secondary undistilled residue in amount equal to 25 about sixty-nine per cent of the feed of primary residue to the secondary circulation tube, the temperature to which the respective feeds should be heated may be reduced to about 515° F. with simultaneous increase in pressure in the still to about 0.16 inch of mercury.

30 The higher fatty acids with which I am principally concerned are the saturated and unsaturated carboxylic acids occurring in vegetable, animal, or marine fats and oils and containing mostly from about ten to about twenty carbon atoms per molecule, such as oleic, linolic, stearic, palmitic, myristic, lauric, etc. The principal use of such acids is in the manufacture of soap and candles. Other impure higher fatty acids which 35 are of less common occurrence such as the higher acids resulting from the oxidation of paraffin may also be purified by distillation in accordance with the present invention.

40 Having thus described my invention, what I claim and desire to secure by Letters Patent is:

45 1. A process of continuously distilling at reduced pressure without the use of an added gaseous medium higher fatty acids from a material containing a substantial amount of higher free fatty acid and thereby separating said material into a component consisting of substantially all of the free fatty acids in substantially pure form, and a component consisting of undistilled residue, comprising continuously passing the material to be subjected to distillation through a heating zone wherein sufficient heat is incorporated in said material to effect substantially instantaneous vaporization of most of the free fatty acids contained therein when subsequently subjected to said reduced pressure, continuously introducing the thus heated material into a hot liquid body of primary undistilled residue contained within a zone maintained at a pressure less than the average pressure in said heating zone and not substantially exceeding 0.5 inch of mercury whereupon most of the free fatty acids vaporize substantially instantaneously, employing the vapors thus formed without the aid of an added gaseous medium to project said residue upwardly against a baffle to form a directionally

controlled curtain of undistilled residue, continuously withdrawing excess undistilled residue from said zone, reheating the said excess residue to incorporate sufficient heat in same to substantially completely vaporize the fatty acids contained therein at the pressure within said zone and thereby leave a secondary undistilled residue, continuously introducing the said heated excess residue into a hot liquid body of said secondary undistilled residue and employing the vapors thus formed to project a stream of said secondary undistilled residue, intimately admixed with said vapors, upwardly against a baffle in a zone at said low pressure so as to form a directionally controlled curtain of secondary undistilled residue, continuously withdrawing the fatty acid vapors and condensing same and continuously withdrawing said secondary undistilled residue.

2. In a process of dry flash distillation of fatty acids including the step of projecting undistilled residue intimately admixed with vaporized fatty acids without the aid of an added gaseous medium against a baffle in a low pressure distillation zone so as to create a curtain of undistilled residue, the steps of removing excess residue over and above the predetermined amount necessary for the admixture projected, reheating the removed residue to incorporate sufficient heat in same to vaporize most of the free fatty acids contained therein at low pressure and thereby leave a secondary undistilled residue, continuously introducing said heated residue into a hot liquid body of said secondary undistilled residue and employing the vapors thus formed without the aid of an added gaseous medium to project a stream of said secondary undistilled residue intimately admixed with said vapors upwardly against a baffle in a zone at said low pressure so as to create a curtain of said secondary undistilled residue.

3. The process in accordance with claim 2 in which the vapors from the first and second va-

porization are combined before being condensed.

4. The process in accordance with claim 2, in which the vapors are separately condensed.

5. The process of claim 2, in which the secondary and primary vaporizations are conducted within the same distillation zone.

6. The process of claim 2, in which the secondary and primary vaporizations are conducted in separate, interconnected zones.

10 7. A process of subjecting to redistillation an undistilled residue from a primary distillation of a fatty-acid-containing material comprising heating the undistilled residue to incorporate sufficient heat in same to vaporize most of the free fatty acids contained therein at low pressure and thereby leave a secondary undistilled residue, continuously introducing said heated residue into a hot liquid body of said secondary undistilled residue and employing the vapors thus formed without the aid of an added gaseous medium to project a stream of said secondary undistilled residue intimately admixed with said vapors upwardly against a baffle in a zone at said low pressure so as to create a curtain of said secondary undistilled residue.

15 8. A process of subjecting to redistillation an undistilled residue from a primary distillation of a fatty-acid-containing material comprising heating the undistilled residue while subjecting same to progressively decreasing pressure to incorporate sufficient heat in same to vaporize most of the free fatty acids contained therein at low pressure and thereby leave a secondary undistilled residue, continuously introducing said heated residue into a hot liquid body of said secondary undistilled residue and employing the vapors thus formed without the aid of an added gaseous medium to project a stream of said secondary undistilled residue intimately admixed with said vapors upwardly against a baffle in a zone at said low pressure so as to create a curtain of said secondary undistilled residue.

VICTOR MILLS.
